UNITED STATES PATENT OFFICE.

SIMON BARLOW, OF OGDEN, UTAH.

FUEL-FEED CONTROL FOR AUTOMOTIVE ENGINES.

Application filed March 31, 1925. Serial No. 19,702.

To all whom it may concern:

Be it known that I, SIMON BARLOW, a citizen of the United States, residing at Ogden, in the county of Weber and State of Utah, have invented new and useful Improvements in Fuel-Feed Controls for Automotive Engines, of which the following is a specification.

My invention relates to improvements in foot-throttle mechanisms, otherwise known as accelerators, as applied to automotive engines, and the objects of my invention are:

First, to provide means by which the idling, or slow-moving, fuel supply to the engine; which is regulated in automotive engine installations usually by hand throttle lever and occasionally by cowl-board pull rod, or not at all, may also be shut off and regulated by the foot throttle, thereby to enable the use of the engine as a brake effectively at and down to the lower speeds, without need of disturbing the hand-throttle setting.

Second, to provide means in connection with the foot-throttle, or accelerator, of automotive engines, by which, with a slight tip of the foot, to the right for instance, the operator may cause the foot-throttle to lock in its then position, when in other than the idling or slow-moving position of such foot throttle, thus enabling the operator, by such slight side pressure of the foot, to hold the foot-throttle in repose against foot weight and in repose against variation of foot pressure due to undulations in the road traveled, and providing relief from nervous and muscular strain of holding the foot throttle at a certain up-in-space position in order to hold a uniform engine speed.

And, what I wish to designate as a third object is, to provide means of carrying out the foregoing two objects with what may be a single mechanism.

I attain these objects by the mechanism illustrated in the accompanying drawings, in which—

Figure 1 is a vertical section on line 1—1, Figure 4, of the entire device, with the exception of means of connection with the carburetter, either with or without co-operation with a hand throttle. Figure 2 is a plan view of Figure 1, showing the foot plates and stop that prevents left plate

being carried with it. Figure 3 is a side-view section of Figure 1, on the line 3—3, omitting foot plates at the top. Figure 4 is a plan-view section of Figure 1, on line 4—4. Figure 5 is an elevation of the gear wheel, its crank arm on one side, and its shaft on one side. Figure 6 is a half vertical section of the gear wheel, showing crank arms and shaft. Figure 7 and Figure 8 are the top and bottom (or front and rear) fulcrum and distance-check pieces. Figures 9, 10 and 11 are diagrammatical illustrations of the functions and movements of the parts of my principal invention, as designated in Figure 9, during the operation of the device to carry out the object hereinbefore designated as the first. Figures 12 and 13 are diagrammatical illustrations of the functions and movements of the parts of my principal invention, as designated in Figure 12, during the operation of the device to carry out the object hereinbefore designated as the second. Figure 14 is a diagrammatical illustration of the functions and movements of the same parts during the operation of the device as a straight or ordinary foot throttle, foot pressure being placed upon the left foot-plate only, or upon both foot-plates at the same time, the left plate being slightly thicker than the right. Figure 15 is a plan view, partly in section and partly in perspective, of the entire device, connected with carburetter and co-operating hand-throttle connections of an automobile. The section is the same as in Figure 1, except that the top fulcrum and distance-check piece has been removed, to better show the gear wheel, its crank and shaft. Figure 16 is a detail illustration of the check sleeve shown in Figure 15, which restricts the action of the usual foot-throttle spring. Figure 17 (the other drawing) is an elevation view of an alternative gear wheel and shaft and crank construction, showing shaft and crank as a single bar. Similar numerals refer to similar parts throughout the several views. The shell, or frame, 1, secured either rigidly or by universal connection to the foot-board 36, of an automobile, constitutes the frame work of the principal mechanism comprising my invention. In such shell the push-rods 9 and 10 reciprocate. Push-rod 9 is integral with foot-plate 11, bears certain gear teeth upon its inner side, and by such

gear teeth is always in mesh with gear wheel 4, and is connected through bellcrank 24, rod 25, bell-crank 26, and rod 27, with the carburetter valve crank-arm 28. Any movement of pushrod 9 is transmitted to crank-arm 28, so long as hand-lever 34, on quadrant 35 (Fig. 15) remains at the same time stationary.

The carburetter valve-crank 28, in all proper automotive installations, turns with the use of very little force. The coil spring 19 returns the through foot-throttle push-rod 9 and its connections, including 28, to the closed foot-throttle position after any depression of foot-plate 11 and such rod 9. Upwards beyond this closed foot-throttle position of push-rod 9 and connections, however, this spring 19 does not act, being prevented from exerting any force at all at that point and beyond, by the sleeve 18. This sleeve is slidably connected to a lug on push-rod 9, as is better shown in Figure 16, and has an open end, the end edges being rounded on the inside to prevent catching upon the spring. The spring 19 passes through this open end of sleeve 18 and is secured to a frame structure of the engine, such as 20. The stopping of the sleeve 18 against frame member 20 prevents further action of spring 19.

For any further upward movement of push-rod 9 and foot-plate 11 above and beyond this closed foot-throttle position, the lug on push-rod 9 slides upon the sleeve 18 without hindrance.

In the arrangement of connections shown by Figure 15, so long as carburetter crank-arm 28 may be turned by a force equal, in one direction, to the tension of spring 19, and equal, in the other direction, to the tension of spring 15, then such crank-arm 28 may be adjusted for idling speed or slow running, or may be regulated for all speeds of running, by and through hand-lever 34 and its connections 33, 32, 24, 25, 26 and 27. This hand-lever 34, if used at all in an automobile equipped with my invention, should be made to act, by rod (as here) or by flexible tube and wire, or otherwise, at right angles to the line of application of any force by push-rod 9, and when so connected does not, when operated, change the position of push-rod 9 and the mechanism connected through gear-wheel 4 to push-rod 9. Thus, the hand-lever 34 is allowed here to retain still its usual function of regulating the idling and slow-running opening of the carburetter valve and its function of an emergency control lever, the springs 15 and 19 taking the reaction when the hand-lever turns carburetter crank 28.

In Figure 15, No. 31 is the engine, and 35 is an extended quadrant upon the steering column, such that hand-lever 34 may be moved through a somewhat wider range than

is usual, the idling position being about the center, or as shown. This to permit shut-off by hand-lever no matter in what position push-rod 9 and foot-plate 11 may be.

For the purposes of this description, I will now consider the left-hand foot-plate, 11, and its push-rod, 9, which are integral, as constituting, when taken alone, the foot-operating part of an ordinary foot-throttle or accelerator as it is found on the medium priced and higher priced automobiles, trucks, and other automotive vehicles of today, with the difference mentioned in the last paragraph, i. e., non-interference of the hand throttle with the position of the parts comprising the foot-throttle. In other words, regulation by means of hand-lever 34 does not reciprocate push-rod 9.

Push-rod 9 is specially shown in Figures 1, 9, 10, 11 and 14, and it is to those figures I will now refer, omitting reference to the carburetter connections hereinabove discussed.

The push-rod 9 may be round or square, or have flanges to help give clearance for other parts; it has gear teeth cut in or built on, as illustrated in Figures 1 and 3; it projects down through the shell, 1, of my invention, and a short distance below the shell it carries the lug to which spring 19, by its sleeve 18, is slidably connected; and it makes connection at the bell-crank 24 with the carburetter.

Now, I press foot-plate 11 with the foot, or press both plate 11 and plate 12, simultaneously. They will both go down, and the entire mechanism will function as a simple foot throttle and open the carburetter valve. Foot-plate 11 is slightly thicker than foot-plate 12, and 11 is on the side nearest the operator's seat. Check-piece 13 is a stop, and imparts to foot-plate 12 and to push-rod 10 any downward motion of foot-plate 11.

Figures 1, 2, 3, 4 and 15 show the position of the parts at the closed-throttle position of the foot mechanism. I will call this the closed foot-throttle position of the parts. Figure 14 shows the position of the parts at almost full foot-throttle depression.

The broken horizontal lines *aa* and *bb*, Figures 9, 10 and 11, show the position of tops of foot-plates 11 and 12, and of the center of shaft 5 of gear wheel 4, respectively, when no gas is being fed by means of the foot-throttle.

With the foot-throttle in such closed position, and the push-rod 9 and 10 and foot-plates 11 and 12, respectively, in the position illustrated by Figures 1 and 15, then I slide the foot to the right against stop 37 (Fig. 15), or, at any rate, with the foot missing plate 11, I depress foot-plate 12 only. The rod 10 is integral with foot-plate 12, and is in mesh by gear teeth with gear wheel 4.

Rod 10 is short, and is retained in its outward position by the coil spring 15, working over the guide rod 14. Upon a slight depression of foot-plate 12, the rod 10 will 5 roll and rotate the gear wheel 4 upon push-rod 9. The center-shaft, 5, of gear wheel 4, will then travel half the distance that is traveled downward by push-rod 10. In its 10 rolling upon push-rod 9, the gear 4, by means of its crank arms, 6, located on either side thereof, will rotate the fulcrum and distance-check pieces 7 and 8 to the left about their common axis 16. These fulcrum and 15 distance-check pieces are illustrated separately by Figures 7 and 8, and will usually be designated "fulcrum and check pieces." They may best consist of stiff steel plates, perhaps three-thirty-seconds of an inch in thickness. They rotate through but a small 20 angle, upon a through-pin 16. If my invention is used only to carry out object designated as the first, these pieces need not have the teeth along one edge of the vertical slot, as are shown, or any means by which the 25 cranks 6 and the shaft 5, or equivalent, would bind in the lower part of the slot of these pieces. On the other hand,—if my invention is used only as a throttle-lock, or check, 30 mechanism, to carry out alone object designated as the second, then these pieces might consist of simply the slot with parallel sides and the teeth, or of such surface and slot that 5 and 6 would bind therein on slight rotation about center shaft 5,—and, indeed, 35 the slots for such a single device might be made integral with the shell or housing of the device. These pieces have, in my invention as illustrated by my drawings, fulcrum-bearing surfaces 39 and 38. These surfaces 40 act simultaneously, when they are brought by cranks 6 underneath the shaft 5, and they prevent further depression of gear 4 within the mechanism and the gear then rotates, under continued depression of push-rod 10, 45 and causes push-rod 9 to be retracted—brought upward—beyond its normal off foot-throttle position.

Upon the continued depression of foot-plate 12, below the position hereinabove mentioned, the bearing surfaces 39 and 38, of fulcrum and check pieces 7 and 8, respectively, will, by the cranks 6, be brought into the downward path of, and beyond the vertical line through the center of, shaft 5, 55 which shaft of course has traveled downward in a line parallel with push-rods 9 and 10,—the gear wheel 4 rolling in mesh with rods 9 and 10. So far, push-rod 9 has remained stationary. As soon as shaft 5 reaches the bearing surfaces 38 and 39 of the fulcrum and check pieces, then the further depression of foot-plate 12 and its push-rod 10 imparts a reverse or upward motion to the push-rod 9 and all its connections, equal to 60 such further downward motion of push-rod

10 beyond the point illustrated by Figure 9. This last is illustrated by Figure 10. The broken line *aa* shows the normal off foot-throttle position of foot-plate 11.

The amount of reverse motion illustrated in Figure 10 is calculated to close the carburettor valve entirely, against any supply of gas needed for idling or slow running, and thus to cause the engine to act entirely, and more effectively, as a brake, and cause the engine to be effective to bring the vehicle or machine to an absolute stop, if foot-plate 12 is held down that long. If the hand-throttle should happen to be set at a greater speed than idling or slow road speed, then the further depression of 12, as illustrated in Figure 11, is calculated to cause sufficient reverse motion of push-rod 9 so as to entirely shut off that fuel supply from the engine, and cause the engine to function effectively as a brake under those conditions as well.

Now, I take the foot off foot-plate 12, and immediately the spring 15 forces push-rod 10 and foot-plate 12 back to their normal off foot-throttle position. And by this same force upon push-rod 10 the spring 15, acting through push-rod 10 and through gear wheel 4, fulcrumed by shaft 5 against stops 22 made part of frame shell, 1, the push-rod 9 and its connections are brought back to normal off foot-throttle position, with only such gas passing to the engine as is allowed by the setting of the hand-lever 34 and its connections.

The mechanism, the parts and mode of operation of which I have just described, comprise the means by which object designated the first is carried out.

When my mechanism is used as is an ordinary foot throttle, the two push-rods and their respective foot-plates maintain the relative positions illustrated by Figures 1, 2, 3 and 15. That is to say, foot-plates 11 and 12 are in the same horizontal plane, except that the top of plate 11 may extend perhaps one sixty-fourth of an inch higher than plate 12, so that foot-plate 11 will take the foot pressure as ordinarily exerted upon a foot-throttle by the right foot of the operator, who sits to the left of the foot-throttle mechanism. But, however that may be, no space at all or, at most, a very slight space, should exist between foot-plate 11 and stop 13 when the parts are in this closed foot-throttle position.

In Figures 12, 13 and 14 the horizontal broken line *cc* marks the normal closed foot-throttle position of the tops of foot-plates 11 and 12, and horizontal broken line *dd* marks the center of the shaft 5 of gear 4, when the parts are in such normal closed foot-throttle position. In Figure 1 they are in such position.

The first slight depression of the foot

upon foot-plate 11, or equally upon foot-plates 11 and 12, takes the gear wheel 4 downwardly, as a unit with push-rods 9 and 10. The distance the parts would move by reason of such slight depression of foot-plate 11, as illustrated by Figure 12, would open the carburetter valve slightly. Figure 14, as hereinbefore mentioned, shows how the parts would be at nearly full depression, 10 using the mechanism as a straight foot throttle.

But, as soon as the center of shaft 5, of gear wheel 4, has reached a point lower down in the slot of fulcrum and check pieces 15 7 and 8 than the bearing surfaces 39 and 38 (Figures 7 and 8), then, by a slight tipping of the operator's foot to the right, foot-plate 12 may be depressed below foot-plate 11, opening the space between plate 11 and 20 check piece 13, and that slight tipping movement and consequent depression of foot-plate 12, will cause a binding by the cranks 6, which are an integral part of gear wheel 4, against a side of the slot in fulcrum and 25 check piece 7 and in fulcrum and check piece 8 (see Figures 7 and 8). Catches of a suitable character, as illustrated in Figures 1, 3, 7, 8, 13 and 15, may be provided in such fulcrum and distance check pieces 7 and 8 30 in order to facilitate this binding and distance-checking action.

Figure 13 illustrates the condition that will then exist, and which may exist at any point during the further depression of the 35 foot-throttle beyond the point shown by Figure 13, and as long as the foot of the operator is allowed to exert more pressure upon the right foot-plate, 12, than upon the left foot-plate, 11, the mechanism will remain locked against further downward motion. The operator's foot may then rest with the heel on the floor and the toe partly upon foot-plate 12 and partly upon foot-plate 11, but tilted slightly so as to give the 40 greater pressure upon 12, and so long as he wishes to continue to feed the same amount of fuel to his engine he may by that means maintain the parts of my mechanism in a locked position. Over bad roads he maintains that tilted position of his foot upon the foot-throttle, with the greater pressure upon foot-plate 12, at whatever throttle opening he desires. And the operator's foot, 45 thus slightly tilted, is in a rather natural position of repose.

Immediately the operator equalizes his foot pressure upon both foot plates, 11 and 12, then the push-rod 9 is unlocked again, and remains under direct foot control. 50 Then the same tilting again, will cause a similar locking in the same or any other position of foot-throttle except when nearly in the closed foot-throttle position, as hereinbefore explained and as illustrated by 55 Figure 12.

To summarize: Having an automobile traveling at say 25 miles an hour, on a rough road, the operator may have his foot slightly tilted to the right, bearing upon both plates 11 and 12, but with the greater force upon 70 12. (Little force is required, though considerable force, such as might be brought to bear in negotiating rough roads, would not disturb the mechanism.) His foot-throttle will be locked against any such 75

downward pressure, so long as he maintains that unequal pressure upon foot-plate 12. The operator wishes to come to almost a full stop at the top of a near-by grade, and he also wishes, we will say, to use his engine 80

as an effective brake down the grade. He takes all pressure off of foot-plates 11 and 12; the foot-throttle mechanism unlocks itself, by the action of spring 15 pressing upwards upon push-rod 10, and by the 85

same means the foot-plates 11 and 12 are returned to their normal off foot-throttle position. The engine is still getting some fuel, by reason of a setting of the hand-throttle lever, 34, for idling and slow running. The operator then moves his foot to the right sufficiently to miss foot-plate 11 entirely, and he applies foot-pressure to 90 foot-plate 12. A reverse, or upward, motion is thereby imparted to push-rod 9 and its carburetter connections, through gear wheel 95

4, fulcrumed upon the bearing surfaces 39 and 38 of fulcrum and check pieces 7 and 8, respectively. By such means the 100 operator is enabled to shut off all fuel supply to the engine and to use the engine as a brake at all speeds, without his having to modify his hand-lever setting before and to remember to reset it afterwards. In

practice at the present time the brakes are 105 used in preference to bothering with changing the hand-throttle setting, and the engine is used as a brake only at the higher speeds and hardly ever to bring the vehicle to any- 110

where near the speed, for instance, of a person walking or to hold the machine at slow speed down a grade.

I have, in my Figure 15, shown a foot stop, 37, against which the operator may bring his foot in order accurately and positively to miss foot-plate 11 when desiring to get the reverse foot-throttle action. An adjustable extension upon foot-plate 12 might be used for the same purpose. Neither 115 is absolutely necessary.

I am aware that prior to my invention locks and catches for foot-throttles have been made, and therefore I do not claim such a particular device broadly.

Of a foot-throttle locking device involving two co-acting foot-plates and push-rods such as mine, and involving a cross-bar pinned at its ends instead of geared, and having a center pin and a crank pin 125 (or the two pins integral), or involving 130

such a means as my gear wheel and its shaft and crank pins, I have not heard, and therefore I desire to claim my locking mechanism broadly enough to include such a cross-bar 5 as the equivalent of my gear wheel.

Of a device to retract a foot-throttle and thereby to shut off all fuel being fed by either hand throttle at the wheel or by pull or turn shaft at the cowl-board or by an 10 open setting of the carburetter valve, I have not heard, and therefore I desire to claim broadly a device to perform that function alone and also a device to perform both the retracting and locking functions in the same 15 mechanism.

I claim:

1. In a fuel feed control for automotive engines, a carburetter valve crank, a through foot-throttle push-rod operatively connected 20 with said valve crank, a hand-operated means also for operating said valve crank and co-acting with said through push-rod but operating at right angles thereto, through means fulcrumed thereon, a spring 25 means of retaining and retracting said through push-rod from downward to normal off position and a sleeve slidably connected to such push-rod as a check on such spring action, a second push-rod adjacent to the 30 first and bearing a stop such that downward movement of the through push-rod depresses said second push-rod, a spring to return said second push-rod and connections to normal off position, a gear wheel operatively in mesh with both said push rods and having crank arms off center and a center shaft, fulcrum-and-distance-check 35 pieces having bearing surfaces and slot co-acting with such shaft and crank arms.

2. In a fuel feed control for automotive engines, a carburetter valve crank, a through foot-throttle push-rod operatively connected with said valve crank, a spring means of retaining and retracting said 40 through push-rod from downward to normal off position and a sleeve slidably connected to such push-rod as a check on such spring action, a second push-rod adjacent to the first and bearing a stop such that downward movement of the through push-rod depresses said second push-rod, a spring to return said second push-rod and connections to normal off position, a gear wheel operatively in mesh with both said push rods and having crank arms off center and a center shaft, fulcrum - and-distance-check pieces 45 having bearing surfaces and slot co-acting with such shaft and crank arms.

3. In a fuel feed control for automotive engines, the combination of a carburetter valve crank, a through foot-throttle push-rod operatively and adjustably connected with said valve crank, a spring means of retaining and retracting said through push-rod from downward to normal off position 50

and a sleeve slidably connected to such push-rod as a check on such spring action, a second push-rod adjacent to the first, a stop on one or the other of said push rods so arranged that downward movement of the 55 through push-rod depresses said second push-rod, a spring to return said second push-rod and connections to normal off position, a gear wheel operatively in mesh with both said push rods and having crank arms off center and a center shaft, fulcrum-and-distance-check pieces having bearing surfaces and slot co-acting with such shaft and crank arms. 70

4. In a foot accelerator mechanism, a foot-operated through push-rod, operatively and adjustably connected to the carburetter, a spring means of retaining and retracting said 75 through push-rod from downward to normal off position and a sleeve slidably connected to such push-rod as a check on such spring action, a gear wheel, a second push rod adjacent to the first, means by which, in connection with said gear, independent depression of the second push rod imparts reverse 80 motion above normal off foot-throttle position to the other push-rod and its connections, a spring to return said second push-rod upward after any change in its 85 position. 90

5. In a foot accelerator mechanism, the combination of a foot-operated through push-rod, operatively connected to the carburetter, a gear wheel, a second push-rod adjacent to the first, means by which, in connection with said gear, independent depression of the second push-rod imparts reverse 95 motion above normal off foot-throttle position to the other push-rod and its connections. 100

6. In a foot accelerator mechanism for automobiles, a foot-operated push-rod operatively connected to the carburetor, a second push-rod adjacent thereto, a cross-member connecting said push-rods, said cross-member bearing a center cross-pin and a vertically off-center cross-pin, members each bearing a slot along which said center pin and off-center pin of said cross-member may 105 slide when both push-rods are depressed simultaneously, and said members bearing catches upon which said off-center and center cross-pins will bind and thereby lock the mechanism if the second push-rod is at any time reciprocated downward a greater distance than the first push-rod, two springs, one to return the first push-rod and one to return the second push-rod upwardly after 110 any change in their positions, and a stop placed upon either push-rod, adapted to cause depression of such second push-rod 115 if the first be depressed. 120

7. In a foot accelerator mechanism for automobiles, a foot-operated push-rod operatively connected to the carburetter, a second 125

130

- push-rod adjacent thereto, a cross-member connecting said push rods, said cross-member bearing a center cross-pin and a vertically off-center cross-pin, a member or members having a slot along which said center pin and off-center pin of said cross-member may slide when both push rods are depressed simultaneously, and against the sides of which said off-center and center 10 cross-pins will bind, and thereby lock the mechanism, if the second push-rod is at any time reciprocated downward a greater distance than the first push-rod, two springs, one to return the first push rod and one to 15 return the second push-rod upwardly after any change in their positions, and a stop placed upon either push-rod, adapted to cause depression of such second push-rod if the first be depressed.
- 20 8. In a foot-throttle locking device combined with a foot-throttle, the combination of a cross-member operatively engaged at its edges with two parallel reciprocating members, one of which is connected with the carburettor, such cross-member having two pins, or one wide lug, sliding along a slot or slots parallel with such reciprocating members and arranged to bind or catch in said slot or slots when the reciprocating 25 members are unevenly reciprocated, spring or springs to return both reciprocating members after any change of position.
9. In a fuel feed control for automotive engines, a carburetor valve crank, a through 30 foot-throttle push-rod operatively connected with said valve crank, a hand-operated means also for operating said valve crank and coacting with said through push-rod but operating at right angles thereto, 35 through means fulcrumed thereon, a second push-rod adjacent to the first and bearing a stop such that downward movement of the through push-rod depresses said second push-rod, a spring to return said push- 40 rods and connections to normal off position, a gear wheel operatively in mesh with both said push rods and having crank arms off center and a center shaft, fulcrum-and-distance-check pieces having bearing surfaces 45 and slot coacting with such shaft and crank arms.
- 50 10. In a fuel feed control for automotive engines, a carburetor valve crank, a through foot-throttle push-rod operatively connected 55 with said valve crank, a second push-rod adjacent to the first and bearing a stop such that downward movement of the
- through push-rod depresses said second push-rod, a spring to return said push- 60 rods and connections to normal off position, a gear wheel operatively in mesh with both said push rods and having crank arms off center and a center shaft, fulcrum-and-distance-check pieces having bearing surfaces 65 and slot coacting with such shaft and crank arms.
11. In a fuel feed control for automotive engines, the combination of a carburetor valve crank, a through foot-throttle push-rod operatively and adjustably connected with said valve crank, a second push-rod adjacent to the first, a stop on one of said push rods so arranged that downward movement of the through push-rod depresses said second push-rod, a spring to return 70 said push-rod and connections to normal off position, a gear wheel operatively in mesh with both said push rods and having crank arms off center and a center shaft, fulcrum-and-distance-check pieces having bearing surfaces 75 and slot coacting with such shaft and crank arms.
12. In a fuel feed control for automotive engines, the combination of a carburetor valve crank, a through foot-throttle push-rod operatively and adjustably connected with said valve crank, a spring means of retaining and retracting said through push-rod from downward to normal off position 80 and a sleeve slidably connected to such push-rod as a check on such spring action, a second push-rod adjacent to the first, a spring to return said second push-rod and connections to normal off position, a gear wheel operatively in mesh with both said push rods 85 and having crank arms off center and a center shaft, fulcrum-and-distance-check pieces having bearing surfaces and slot coacting with such shaft and crank arms.
13. In a fuel feed control for automotive engines, a carburetor valve crank, a reciprocating rod operatively connected with said valve crank, a second reciprocating rod adjacent to the first, and bearing a stop 90 such that in one direction reciprocation of the first rod reciprocates the second, spring means to return said reciprocating rods and their connections to normal off position, a wheel operatively connected to both of said rods and having crank arms off-center and 95 a center shaft, fulcrum and distance check members having bearing surfaces and slot coacting with such shaft and crank arms.
- 100 110 SIMON BARLOW.
